Primary Examiner — Catherine S Posthauer(74) Attorney, Agent, or Firm — Belles Katz LLC(57) CLAIM

The ornamental design for an oven, as shown and described.

DESCRIPTION

FIG. 1 is a top front perspective view of an oven according to the new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines represent portions of the oven that form no part of the claimed design.

1 Claim, 8 Drawing Sheets(56)
